UNITED STATES PATENT OFFICE.

SEMEON SKERPAN, OF DETROIT, MICHIGAN.

ENVELOPE.

Application filed August 7, 1924. Serial No. 730,661.

This invention relates to new and useful improvements in envelopes.

The primary object of this invention is to provide an envelope with an improved 5 form of closing or sealing means.

A further object of the invention is to provide a novel body portion of an envelope and improved means for connecting the parts to form the same.

10 Other objects and advantages of the invention will be apparent during the course of the following description.

In the accompanying drawings forming a part of this specification and in which 15 like numerals are employed to designate like parts throughout the same,

Figure 1 illustrates in plan view the blank employed for forming the envelope before the edges of the same have been gummed,

20 Figure 2 illustrates a plan of the envelope after the edges have been gummed and two flaps employed for forming the body portion of the envelope properly connected,

Figure 3 illustrates a plan view of the 25 envelope after all of the flaps employed for forming the body portion of the envelope have been connected and sealed together,

Figure 4 illustrates a longitudinal sectional view of the envelope showing the 30 closure flap with its sealing tongue folded down in engagement with the body portion of the envelope and further illustrates said sealing tongue prior to the sealing of the same to the said body portion,

35 Figure 5 illustrates a similar view to Fig. 4 with the sealing tongue carried by the closure flap sealed to the body portion of the envelope,

Figure 6 illustrates a transverse sectional 40 view taken upon lines VI—VI of Fig. 3,

Figure 7 illustrates a transverse sectional view taken upon line VII—VII of Fig. 8, and

Figure 8 illustrates a plan view of the 45 envelope after it has been sealed closed.

In the drawings, wherein for the purpose of illustration is shown a preferred embodiment of this invention, in Fig. 1, the numeral 5 illustrates the front wall of the body

50 portion of the envelope, to one longitudinal edge of which is integrally formed the bottom flap 6 having the outwardly converging edges 7 which terminate in the blunt point 8. Formed transversely of the bottom flap

55 7 in proximity to the blunt end are the spaced slits 9 which extend in parallelism to

each other. The bottom flap 6 is further provided with a longitudinally extending slot 10 which has a length substantially equal to the distance between the parallel 60 slits 9 and has its ends terminating in close proximity to the inner ends of said slits 9. This bottom flap 6 is intended to be folded upon the front wall 5 of the body portion of the envelope on the dotted line —a—. 65 Formed integrally with the end edges of this front wall 5 are the end flaps 11 and 12 which are of substantially triangular formation and have the bifurcated tongues 13 and 14 formed at the outer ends thereof. 70 The furcations 15 and 16 of these bifurcated tongues 13 and 14 are of unequal size, the furcations 15 being smaller than the furcations 16 and intended to be folded upon the lines —b—, the furcations 16, being intended 75 to be unfolded in respect to the end flaps 11 and 12. These end flaps are intended to be folded upon the dotted lines —c—. The remaining edge of the front wall 5 of the body portion of the envelope has formed 80 integrally therewith the closure flap 17 which is provided with the integrally formed sealing tongue 18 at its outer edge. It is intended that the edges 11^a and 12^a of the end flaps 11 and 12 and the furcations 85 15 of these flaps be gummed, as illustrated in connection with the end flap 11 in Fig. 2. The outer edges of the closure flap 17 are intended to be gummed as illustrated in Fig. 2 and the sealing tongue 18 is also intended to be gummed.

In forming the body portion of the envelope, the bottom flap 6 is first folded upon the line —a— for causing it to overlap the front wall 5. Either end flap 11 or 12 may 95 then be folded upon the line —c— for causing its gummed edge to be moved into engagement with the outer face of the bottom flap 6 to which it is sealed. The furcation 15 is intended to be inserted through the adjacent slit 9 for the purpose of permitting its gummed surface to be sealed to the inner face of the bottom flap 6. The remaining furcation 16 of this end flap is illustrated as 100 overlying the portion of the bottom flap positioned between the parallel slits 9. The remaining end flap should then be folded upon its dotted line —c— and connected to the bottom flap in the same manner as described in connection with the first end flap. 105 The body portion of the envelope is now 110 ready for receiving a letter or the like.

1,600,853

.8321,12 Aug 2, 1969

To seal the envelope, the closure flap 17 is to be folded upon the body portion of the envelope, at the line —d— and the sealing tongue 18 should then be inserted into the envelope through the slot 10. The gummed portion of this sealing tongue should then be forced against the inner surface of the portion of the bottom flap positioned between the parallel slits 9 and sealed thereto, as best illustrated in Figs. 5 and 7. The envelope is now in a proper condition to be mailed.

It will readily be seen that the body portion of the envelope has its end flaps not only secured to the bottom flap by the sealing gum or adhesive substance, but also has the furcations 15 inserted into the interior of the body portion of the envelope and sealed to the inner face of the bottom flap, thereby insuring against unintentional separation. The closure flap 17 is not only sealed to the body portion of the envelope by an adhesive substance, but it is also provided with a sealing tongue that is inserted into the envelope and sealed to the inner face of the bottom flap, thereby insuring against accidental opening of the envelope.

It is to be understood that the form of this invention herewith shown and described

is to be taken as a preferred example of the same, and that various changes in the shape, size, and arrangement of parts may be resorted to without departing from the spirit of the invention or the scope of the subjoined claim.

Having thus described the invention, I claim:

In an envelope of the type described, a front wall, end, bottom and closure flaps, the bottom flap having a pair of parallel slits extending to the free edge thereof and a cross slot positioned inwardly of the slits with the bottom flap lying adjacent the front wall, each of the end flaps being bifurcated at their outer ends and folded inwardly to overlie the bottom flap with one furcation of each flap extended through the adjacent slit toward the front wall and folded outwardly, and a sealing tongue on the closure flap extended through the said slot and folded inwardly to underlie the adjacent superposed portions of the end and bottom flaps, substantially between the oppositely extending extremities of said end flaps, whereby displacement is adapted to be prevented.

In testimony whereof I affix my signature.

SEMEON SKERPAN.
